UNITED STATES PATENT OFFICE.

EDWARD B. POGGENSEE, OF CHICAGO, ILLINOIS.

BOTTLE-WASHING MACHINE.

SPECIFICATION forming part of Letters Patent No. 728,006, dated May 12, 1903.

Application filed November 17, 1902. Serial No. 131,741. (No model.)

To all whom it may concern:

Be it known that I, EDWARD B. POGGENSEE, a citizen of the United States, residing at Chicago, in the county of Cook and State of Illinois, have invented a certain new and useful Improvement in Bottle-Washing Machines, of which the following is a full, clear, concise, and exact description, reference being had to the accompanying drawings, forming a part of this specification.

My invention relates to bottle-washing machines wherein water is employed under pressure to wash bottles, brushes being employed for effecting the thorough application of the water.

My invention has for its particular object the provision of an improved form of detachable brush, which is very simple in construction and which may be readily removed from its support or stock, so as to enable another to be substituted therefor.

Hitherto tubular stocks have been employed formed of open-ended tubes provided with plugs for insertion therein and having holes therethrough through which the wire stem for the bristles of the brush is passed, and which is also further apertured to permit of the passage of water therethrough to the brush. The plugs after being driven in place are secured in position by means of a rivet passed through the tube and into the plug. To those skilled in the art it will be appreciated that this rivet when loosened, as frequently happens, will injure the machine. Moreover, the plug in being driven into place frequently splits the tube. Another objection is that the loop end with the wire stem has to be drawn extremely close about the plug in order to enable the stem to maintain a given direction with respect to the tubular stock. Furthermore, the presence of the wire loop within the tube and the plug limits the rate of flow through the plug, which might otherwise be increased, if desired. The

greatest objection to this former type of brush resides in the difficulty of removing the brushes when worn out to replace the same with fresh brushes. It is obvious that the bristles will be rapidly worn away, and the difficulties are magnified as a consequence of the frequent renewals.

In my invention the tubular stock is made

in one integral structure—that is, tubular for a part of its way and closed for the balance of the way, with the exception of the apertures through which the water is to pass. Instead of providing apertures for the reception of the wire stem that have communication with the chambered portion of the stock the wire stem is held in place by being passed through a hole that extends diametrically through the solid end of the plug, and preferably in such a way as not to be in communication with the water-conveying aperture or apertures in the plug. This diametrically-disposed hole will prevent lost motion longitudinally between the wire stem and the stock, while longitudinal grooves engaging the sides of the loop maintain the stock and stem in proper alinement. In this way a very cheap construction is secured and one that is very durable and in which the brushes may readily be replaced. There is, furthermore, absolutely no danger on the part of the novel construction to injure the bottle-washing machine by reason of any loosening of rivets or other malformation, which may be totally avoided.

I will explain my invention more fully by reference to the accompanying drawings, in which—

Figure 1 is a side elevation of the brush constructed in accordance with the invention. Fig. 2 is a view at right angles of the stem shown in Fig. 1 and the portion of the wire stem engaging the same. Fig. 3 is a longitudinal sectional view through the stock on a plane coincident with the plane of the loop. Fig. 4 is a longitudinal sectional view at right angles to the direction in which Fig. 3 is taken. Fig. 5 is a plan view on line 5—5 of Fig. 1. Fig. 6 is a view in elevation, partially in section, taken in the same direction in which Fig. 2 is taken, the wire stem, however, being removed.

Like parts are indicated by similar characters of reference throughout the different figures.

The stock *a* is preferably circular in contour and made tubular throughout the greater part of its length at *b*, which tubular portion is desirably threaded throughout, so as to receive the correspondingly-threaded end of the water-service pipe, forming a component

part of the bottle-washing machine. The stock is preferably vertically disposed with its solid ends *c* uppermost, this end *c* having longitudinal apertures *d* extending therethrough, which apertures are in direct communication with the interior of the portion *b*, so that water may be passed therethrough to the brush *e*, held above the stock in the manner to be hereinafter set forth. The hole *f* 5 diametrically or transversely passes through the solid portion of the stock and preferably between the longitudinal apertures *d*, through which hole the wire *g* is passed, the wire being desirably passed through this hole substantially straight, being thereafter twisted, so as to engage the fibers or bristles *h* between its spirals. At the end of the stem *g* thus formed there is shown a supplemental tip *i*, that has its fibers disposed longitudinally of 10 the stem and the stock instead of transversely, as is the case with the bristles *h*. In order that the wire stem may form a rigid continuation of the stock, the sides of the stock are preferably longitudinally recessed 15 or grooved at *k*, these recesses being preferably of sufficient depth, so that the wire may be entirely concealed within the same, being flush with the outer periphery of the stock. It will be apparent that the fixture of the wire 20 stem with respect to the stock is not at all dependent upon the compactness of the loop, but is rather determined by the disposition of the wire within the aperture *f* and recesses *k*. It will also be apparent that none of the 25 fluid-space within the stock is occupied by the wire, by reason of which the solid end of the stock may be apertured to a considerable degree to permit the flow of water therethrough to a desired extent. Moreover, no 30 rivets are employed, and the machine-work is greatly simplified, as there are no plugs to be inserted within the bores. The wire stems may, furthermore, be very readily removed, 35 as will be apparent.

It is obvious that changes may readily be 45 made in the device of my invention without departing from its spirit, and I do not, therefore, wish to be limited to the precise construction shown; but,

Having thus described my invention, I 50 claim as new and desire to secure by Letters Patent—

1. The combination with a stem carrying a brush, of a tubular stock for the stem, through which stock the water may be passed to the 55 brush, the said stock being apertured transversely and longitudinally grooved at the exterior to afford locking engagement between the stem and the stock, substantially as described. 60

2. The combination with a tubular stock having a solid end integrally formed therewith and longitudinally apertured to permit of the passage of water therethrough, of a wire brush-stem looped through the stock, the 65 said stock being apertured transversely and provided with two longitudinal grooves upon its exterior to afford locking engagement between the stem and the stock, substantially as described. 70

3. The combination with a tubular stock, having a solid end integrally formed therewith and longitudinally apertured to permit of the passage of water therethrough, and further provided with an opening extending 75 transversely through the solid end, of a wire stem looped through said opening and a brush carried by the stem, the exterior of the stock being longitudinally recessed and receiving the side portions of the loop substantially as 80 described. 70

In witness whereof I hereunto subscribe my name this 12th day of November, A. D. 1902.

EDWARD B. POGGENSEE.
